WATER CONTROL MECHANISM FOR CONCRETE MIXERS

Filed July 14, 1927

2 Sheets-Sheet 2

FIG. 11

UNITED STATES PATENT OFFICE.

GEORGE EVANS WEBB, OF MILWAUKEE, WISCONSIN, ASSIGNOR TO KOEHRING COMPANY, OF MILWAUKEE, WISCONSIN, A CORPORATION.

WATER-CONTROL MECHANISM FOR CONCRETE MIXERS.

Application filed July 14, 1927. Serial No. 205,663.

Concrete mixing machines of certain common types in use involve a construction including a mixing drum, a loading skip for supplying dry aggregates to the drum for mixing, a water tank or supply to provide the necessary water forming a part of every batch of mixed concrete, and suitable means to discharge the drum of the completely mixed concrete.

10 In machines of the above class requirements are becoming more and more strict in relation to insuring good concrete and these requirements take into account the necessity for accurately proportioning the 15 water and the cement contents of the mixed aggregates.

With a view to subserving the object of accurately maintaining a proper water-cement ratio, and more specifically in order 20 to prevent the passage of water from the water supply means to the mixing drum until there is an ample and accurately determined quantity of water to be supplied, the present invention has been evolved.

25 In the carrying out of my invention I utilize safety or locking provisions whereby the skip which charges the mixing drum with the dry aggregates cannot be operated to perform the above function until there is 30 sufficient water in the water supply tank to be admixed with the aggregates when they reach the drum. The locking provisions above referred to are controlled by a special type of pressure controlling contrivance 35 operated by the pressure in the main supply line which carries the water to the mixing drum water supply tank.

My invention will prevent, therefore, the inadvertent or purposeful mixing of batches 40 of concrete in a concrete mixer when a sufficient supply of water to maintain a predetermined water-cement ratio is not at hand and ready to be fed to the mixing drum.

With the foregoing and other objects in 45 view, my invention is fully presented in the accompanying drawings in which:

Figure 1 is a reduced side view of a concrete mixing machine of the type to which

my invention may be advantageously applied.

Figure 2 is an enlarged side view showing more clearly the locking device which co-operates with the clutch operating means used to control the ascent and descent of the loading skip of the mixer.

Figure 3 is a front view of the main parts shown in Figure 2.

Figure 4 is a detailed view showing more clearly the pressure controlling device for the locking contrivance.

Figure 5 is a top plan view of the control device, parts being broken away.

Since to those versed in the art the general construction of concrete mixing machines in use today is understood, it is only necessary to refer generally to such machines as comprising a drum A, a loading skip B, cables C for raising said skip, and suitable clutch means D for throwing into action and releasing the cable operating drum whereby to raise and lower, respectively, the skip. In conjunction with the machine there is usually provided a water supply tank E having a discharge pipe leading into the drum to supply water thereto, said tank being filled at regular intervals, as customary, with water supplied from a supply main 1, which may be a pipe leading to any source of supply of water under pressure. All of the foregoing features are old in the art and are exemplified by United States Letters Patent to Lichtenberg, No. 1,328,635, issued January 20th, 1920.

For the operation of the clutch D, I employ a lever 2, connected by a rod 3 with a clutch knockout lever 4, pivoted suitably at 5 to the framework of the machine. The lever 4 carries a knockout arm 6 adapted to be struck by an abutment screw 7 on the pivoted supporting bracket 8 of the loading skip 9 when said skip reaches a certain point in its upward movement in charging its contents into the drum of the mixer. The purpose of the cooperation of the parts 6 and 7 is to enable the movement of the skip as it reaches its upper limit to knock out the

clutch D and discontinue the upward pull of the cables C, thus causing stoppage of the skip movement at charging position.

My invention largely comprises the provision of a lock member 10 arranged to engage the lever 4, as seen in Figure 2, and pivotally mounted at 11 on a bracket 12. The bracket 12 supports a pressure diaphragm casing 13 containing, as seen in Figure 4, the pressure diaphragm 14 adapted to be acted on at its upper side by pressure of water supplied to the casing 13 by a pipe 15 which leads off to a point of connection 16 with the water supply main 1. Pipe 15

10 may be provided with a cut-off valve 17 in its length. The diaphragm 14 is normally uppressed by a spring 18, and a rod 19 connects the diaphragm 14 with a projection 20 on the locking member 10. A drain and

15 pressure gauge supporting pipe 21 extends also from the casing 13 and is equipped with a drain cock 22 and the pressure gauge 23.

With the parts of my invention constructed as stated, the operation is as follows:

20 Assuming that the water supply tank E is filled with the water necessary for a batch of concrete to be mixed by the mixing drum A, the pressure of water in the casing 13, supplied from the water main 1, will be

25 sufficient to cause downward movement of the diaphragm 14 to lower the lock member 10 so that it does not engage the clutch knockout lever 4. Under such conditions no interference with the operation of raising

30 the skip 9 is present and the drum A may be readily charged at any time with the dry aggregates supplied to said skip.

Should it happen, however, that at the time the operator of the machine wishes to

40 raise the skip 9 there is not sufficient water in the tank E to be used for the batch to be mixed in the drum A, the condition will involve the passing of the water from the main 1 to the tank E. When the water is

45 passing from the water main 1 to the tank E the pressure in the former is lowered, and immediately said pressure is lowered, as will be the case under the condition now described, the spring 18 will force the dia-

50 phragm 14 upwards and raise the lock member 10 to a position engaging the knockout lever 4. While in such position as is shown in Figure 2, the operator of the machine cannot throw the clutch lever 2 so as to

55 raise the skip. As soon as the tank E has filled from the water main 1 the full pressure in the main 1 is restored and will pass through the pipe 15 to the diaphragm casing 13 and actuate the diaphragm to lower the

60 lock member 10 in self evident manner. When so lowered, of course, the operator may freely shift the lever 2 to throw on the clutch D and raise the skip 9.

Having thus described my invention

65 what I claim as new, and desire to secure

by Letters Patent of the United States, is:—

1. In a concrete mixing machine, in combination, a mixing drum, a charging means for supplying aggregates to the drum, water supply means for the drum, operating means for causing the charging means to supply aggregates to the drum, and instrumentalities for preventing operation of the last mentioned means when a sufficient quantity of water is not available at the water supply means for properly charging the mixing drum with an adequate amount of such water as required by the batch to be mixed in said drum.

2. In a concrete mixing machine, in combination, a mixing drum, a water supply therefor, means to charge aggregates into the drum, and mechanism for preventing operation of said charging means when an insufficient amount of water is available at the water supply for effecting a proper admixture of aggregates and water in the drum.

3. In a concrete mixing machine, in combination, a mixing drum, a water supply main therefor, an aggregates charging skip for said mixing drum, and means controlled by pressure in the water supply main for governing the action of the aggregates charging skip.

4. In a concrete mixing machine, in combination, a mixing drum, an aggregates charging skip therefor, a water tank, a water supply main for the tank, hoisting means for operating the skip, and means controlled by pressure within the main for governing the operation of the hoisting means for the skip.

5. In a concrete mixing machine, in combination, a mixing drum, an aggregates charging skip therefor, a water tank, a water supply main for the tank, hoisting means for operating the skip, and means controlled by pressure within the main for governing the operation of the hoisting means for the skip, including a locking device and a pressure operated diaphragm connected therewith, the hoisting means for the skip including clutch mechanism controlled by said locking member.

6. In a concrete mixing machine, in combination, a mixing drum, a loading skip therefor, a water tank to supply water to the drum, a water supply main connected with the tank, clutch mechanism for controlling the raising of the skip, a lock device for said clutch mechanism, and means controlled by variation of pressure in the water supply main for governing the action of said locking device to render it operative on the clutch mechanism when insufficient water is in the supply tank to meet the requirements for predetermined mixing in the drums and for releasing said clutch mechanism when there is ample water in the supply tank for use with a required batch mixture in the drum.

7. In a concrete mixing machine, in combination, a mixing drum, a water supply tank therefor, a supply main leading to said tank, a loading skip, clutch mechanism for hoisting said skip, a lock for engaging the said clutch mechanism for preventing hoisting action thereof, a pressure device, including a pressure diaphragm, connected with

said lock device to operate the same, means for conducting pressure from the water supply main to said diaphragm to act thereon, and means to operate the diaphragm to render the lock device inactive on reduction of pressure acting on said diaphragm. ¹⁰

In testimony whereof I affix my signature.

GEORGE E. WEBB.
